United States Patent Office.

SOLOMON H. GREENBAUM, OF NEW YORK, N. Y.

Letters Patent No. 96,222, dated October 26, 1869.

IMPROVEMENT IN HAT-TIPS.

The Schedule referred to in these Letters Patent and making part of the same.

To all whom it may concern:

Be it known that I, SOLOMON H. GREENBAUM, of the city, county and State of New York, have invented a new and useful Improvement in Hat-Tips; and I do hereby declare that the following is a full, clear, and exact description thereof, reference being had to the accompanying drawings, and to the letters of reference marked thereon, making part of this specification.

The nature of my invention consists in providing the hat-tip with a box or cavity, sunk in the centre thereof, and closed by a door which is fastened by a small button or spring, the whole constructed of a material so light as to add but little to the weight of the hat, and giving the inside of the hat an ornamental appearance, while affording a convenient receptacle for small toilet-articles, visiting-cards, rail-road-tickets, memorandum-books, and numerous other articles of the same sort, and furnished at the back with a miniature almanac.

To enable others skilled in the art to make and use my invention, I will proceed to describe the manner and process of making the same.

I take a hat-tip, constructed in any of the known ways, and make an opening, of the required size, for the box or pocket in the centre of the tip, which opening may be either square or oval, or any regular shape, and of any size that may be required. The size and shape I prefer is a square about one and one-half inch by two and one-half, for an ordinary hat. This opening is shown in Figure 1 on the accompanying drawings.

In making the opening, I only cut through the tip or lining on three sides of the proposed opening, leaving the fourth side *h* upon fig. 1, uncut, so that the portion cut out may serve as the door, and the uncut side as the hinge. I then construct a box, of paper or cork, or some equally light material, adapted to the size of the opening, and varying in depth according to the distance of the tip from the crown of the hat, from about one-sixteenth of an inch to one and one-half inch, as may be required.

The method of constructing this box, which I prefer, is by cutting out the material in the shape represented in Figure 2, in which A is the bottom of the box, and B B B B the sides, and folding the sides along the dotted lines, which may be done either by marking the line of the folds with a pointed instrument, or bending the material along such lines under a die or former.

These folds should be made so that the sides of the box may stand at right angles with the bottom, and the top of each side folded back so as to form a means of fastening the box to the back of the tip, as represented in Figure 3, which shows a section of the box when folded, *a* and *b* being the point of folding.

The hinge of the door of the opening is strengthened by pasting muslin on the inside, and the door made firmer by pasting a piece of pasteboard or similar material upon its inside surface. The box is then fastened to the back of the tip by glue, shellac, or any proper adhesive material, and may be lined or colored and furnished with a miniature almanac.

The door is furnished with a small button, which plays into an opening in the side of the box, shown at *d d*, fig. 2, and the outside may be provided with a miniature looking-glass, and ornamented by gilt lines, or any device printed upon the silk of the tip.

Figure 4 represents the opening, with the door in perspective.

In conclusion, I would observe that while I have described my invention as applied to what are known as "hat-tips," yet the same may be used in connection with other portions of the interior of the hat. For instance, the box or closet may be secured or applied to the top, or any other suitable part of the interior of the hat-body, or to any part which may be employed in lieu of the tip, and the door, instead of being hinged, can be arranged in other ways, so as to open and close the box. And the invention is also adapted to be used, not only with hats, but with any other article of head-dress. I do not, therefore, limit my claims to the precise details herein given to illustrate the manner in which my invention can best be carried into effect; but

What I claim, and desire to secure by Letters Patent, is—

1. A hat, or other article of head-dress, in the interior of which is formed or arranged a closet or box, closed by a door, substantially as and for the purposes herein shown and described.

2. A hat-tip, furnished with a closet or box, closed by a door, substantially as herein shown and described.

SOLOMON H. GREENBAUM.
